DESIGN FOR A TEXTILE FABRIC

Agnes S. Selverstone, Brooklyn, N. Y., assignor to I. B. Kleinert Rubber Company, New York, N. Y.

Application February 18, 1939, Serial No. 83,076

Term of patent 7 years

To all whom it may concern:

Be it known that I, Agnes S. Selverstone, a citizen of the United States, residing at Brooklyn, New York, in the county of Kings and State of New York, have invented a new, original, and ornamental Design for a Textile Fabric, of which the following is a specification, reference being had to the accompanying drawing, forming a part thereof.

The figure is a plan view of a textile fabric showing my new design. The dot and dash lines on the drawing outline substantially a design unit, which unit is repeated in regular succession as indicated by the extensions beyond the unit boundaries.

I claim:

The ornamental design for a textile fabric, as shown and described.

AGNES S. SELVERSTONE.
